UNITED STATES PATENT OFFICE.

HOWARD J. MURPHY, OF READING, MASSACHUSETTS, ASSIGNOR, BY MESNE ASSIGNMENTS, TO THE BASSICK MANUFACTURING COMPANY, OF CHICAGO, ILLINOIS, A CORPORATION OF DELAWARE.

LUBRICATING APPARATUS.

Application filed March 14, 1922, Serial No. 543,651. Renewed January 20, 1928.

This invention pertains to improvements in lubricating apparatus. It is, among the objects of the invention to provide lubricating apparatus in which a lubricant-receiving part may be quickly attached to and detached from a lubricant-expelling device while minimizing the opportunity for leakage or loss of lubricant.

In the drawings, which show a preferred form of one embodiment of my invention:

Figure 1 is a side elevation of a lubricant-expelling device engaged with a lubricant-receiving nipple;

Fig. 2 is a central, longitudinal section through the nozzle portion of the device illustrated in Fig. 1, being partly in elevation;

Fig. 3 is a section on the line 3—3 of Fig. 2, showing the relation of the parts in coupled relationship;

Fig. 4 is a view similar to Fig. 3, showing the relationship of the parts when uncoupled;

Fig. 5 includes an end and a side elevation of a preferred form of nozzle sleeve;

Fig. 6 includes an end and a side elevation of a preferred form of connecting sleeve;

Fig. 7 includes a side and an end elevation of a preferred form of sealing part;

Fig. 8 illustrates two cooperating valve parts, more fully described hereinafter; and

Fig. 9 is a section on the line 9—9 of Fig. 2.

Referring to the drawings and to the preferred form of my invention selected for illustrative purposes, I have shown a lubricant-expelling device including the usual barrel 9 containing a plunger of the usual construction and actuated by a screw-threaded stem 10 engaging the rear head 11 of the gun. At the discharge end of the gun, I have provided coupling means for engagement with a lubricant-receiving nipple 12 having a lubricant-receiving passage therethrough, which may be sealed at its receiving end by the usual check-valve 13. The nipple illustrated is provided with lateral projections 14, which in the construction illustrated present a square like the head of a cap screw. The preferred form of coupling illustrated includes a nozzle part 15 presenting at its end a square aperture 16 interiorly

cylindrical so as to provide flanges 17 which may underlie the projections on the nipple when turned relative thereto. Within the nozzle part or sleeve 15, I have provided a sealing part 20 movable toward and from the flanges 17 by inclined means typified by the screws 21, 21 engaging inclined slots 22 in the sleeve.

To permit turning of the nozzle sleeve without corresponding turning of the sealing part, I have provided a connecting sleeve 30, shown in detail in Fig. 6, having a squared aperture therein into which may fit the head of the lubricant-receiving nipple 12 and also a squared end 31 of the sealing part 20.

By making the connecting sleeve 30 separate from the sealing disc or part 20, I am enabled to maintain it always in engagement with the inner face of the flanges 17, so that there will be no opportunity for dirt or other foreign matter to get thereunder when the sealing part 20 is retracted and the lubricant nipple removed. The sealing part 20 is apertured at 32 to permit passage of lubricant therethrough, and, rearwardly of the sealing part 20, I have provided a chamber 33. The sealing part 20 carries a sealing washer 34 at the end next to the nipple and preferably provides, as illustrated, a sealing washer 35 at its opposite end to prevent leakage between the sealing part and the nozzle sleeve 15.

Considering the parts thus far described, it will be understood that when the nipple 12 is entered in the nozzle sleeve 15 and the nozzle sleeve 15 is turned, there will be no corresponding turning movement of the sealing part 20 because the connecting sleeve 30 opposes such turning movement, but the sealing part 20 will press the sealing washer 34 against the lubricant-receiving face of the nipple 12 while leaving the lubricant-receiving opening therein free to receive the lubricant through the passage 32 in the sealing part 20.

Cooperating with the parts hereinbefore described, I have provided valve mechanism controlling the passage of lubricant to the coupling and, in that form of my invention illustrated, I have provided coordinated means providing for deferred operation of

the valve pursuant to coupling and for deferring the operation of the coupling means during uncoupling until after closure of the valve means.

5 In the preferred form of my invention illustrated, I effect this by maintaining the valve parts in their closed position until after coupling is effected and by then permitting opening of the valve without further 10 movement of the coupling parts.

Referring to Fig. 2 of the drawings, the coupling sleeve 15 is connected to the barrel 9 through an outer sleeve 50 and clutch means is provided opposing relative movement between this outer sleeve and the coupling sleeve until after coupling is effected. The clutch means in question may take the form of the ball 51 (Fig. 4) which, until coupling is completed, is carried partly by 20 the coupling sleeve 15 but is pressed into a notch 52 in the outer sleeve by the outer wall of the sealing part 20, as viewed in Fig. 4. When coupling is effected, the ball 51 will have been turned until it comes opposite the 25 depression 54 in the sealing part 20. By this time, the sealing washer 34 will have been sufficiently pressed against the nipple to make a tight joint and the ball or clutch 51 will pass out of the notch 52 in the outer 30 sleeve, permitting turning of the outer sleeve relative to the coupling sleeve, as viewed in Fig. 3. Carried by the coupling sleeve 15, I have provided a valve part 55 (Fig. 2) and carried by the outer sleeve 50, I have provided a valve part 56. These valve parts, in 35 the form of my invention illustrated, are turned relative to one another to open the valve. Therefore, when the outer sleeve 50 turns relative to the coupling sleeve 15, the 40 parts of the valve illustrated will be brought into line (as shown in Fig. 2) so that lubricant may pass therethrough, and, to prevent further movement of the valve part 56, I have provided a slot 57 (Fig. 9) in the coupling sleeve 15 and a pin 58 fixed in the outer sleeve 50 adapted to engage the slot 57. The lubricant-expelling device is now 45 coupled to the nipple and the part to be lubricated may have the desired amount of lubricant fed to it by appropriate rotation of the screw-threaded stem 10.

Assuming it is now desired to uncouple the parts, the co-ordinated control means permits such uncoupling by turning of the 5 barrel of the device in counter-clockwise

direction, viz, the direction opposite to that which effected the coupling and valve-opening operations. The coupling, however, cannot be uncoupled until the valve is closed, because no relative turning movement of the sealing disc 20 and nozzle sleeve 15 can be effected until the outer sleeve 50 has been turned sufficiently to permit the clutch 51 to come out of the recess in the sealing part 20 and into the recess 52 in the outer sleeve. 60 When this occurs, the valve will be closed and the outer sleeve and coupling sleeve will turn together relative to the sealing part 20 until uncoupling is completed by retraction of the sealing part 20 by operation of the 65 pin and slot means 21, 22. During this retraction, the connecting sleeve 30 will not have retracted because of its sliding engagement with the sealing part 20.

While I have shown and described a preferred form of one embodiment of my invention, it will be understood that changes involving omission, substitution, alteration and reversal of parts, and even changes in the mode of operation, may be made without departing from the scope of my invention, 70 which is best defined in the following claims.

Claims:

1. Lubricating apparatus including a lubricant compressor having a nozzle presenting a valve part and a sealing part assembled therewith reciprocable in said nozzle by rotary movement transmitted to said nozzle when engaged with a lubricant receiving nipple, said valve independent of said sealing part and disposed rearwardly thereof. 85

2. Lubricating apparatus including a lubricant compressor having a nozzle sleeve, a coupling and reciprocable sealing mechanism for connection with and disconnection from a lubricant-receiving nipple, an axially stationary, rotary valve, and clutch means operatively interposed between said nozzle sleeve and said coupling and sealing means, said clutch means locking said coupling 100 mechanism and said sleeve against relative rotation to permit coupling and sealing operation without opening said valve, said clutch means thereafter locking said coupling and sealing mechanism against relative rotation, 105 thereby to permit rotation of said sleeve for valve opening operation.

In testimony whereof, I have signed my name to this specification.

HOWARD J. MURPHY.
